United States Patent

Des. 241,284
Patented Sept. 7, 1976

241,284

TIE

John P. Johnston, Tamuning, Territory of Guam (Coty Towers Suite 301, 731 Amana St., Honolulu, Hawaii 96814)

Filed Aug. 21, 1974, Ser. No. 499,318

Term of patent 14 years

Int. Cl. D2—05

U.S. Cl. D2—352

FIG. 1 is a front perspective view of a tie showing my new design;

FIG. 2 is a rear elevational view with part of the strands shown as broken away for convenience of illustration; and

FIG. 3 is an enlarged bottom plan view with the top arc of the strands omitted and the bottom of the strands shown as cut away for convenience of illustration.

I claim:

The ornamental design for a tie, substantially as shown and described.
